UNITED STATES PATENT OFFICE.

ALEXANDER E. LITTLE, OF LYNN, MASSACHUSETTS, ASSIGNOR, BY MESNE ASSIGNMENTS, TO THE LITTLEWAY PROCESS COMPANY, OF LYNN, MASSACHUSETTS, A CORPORATION OF MASSACHUSETTS.

BOOT AND SHOE.

Application filed August 5, 1922. Serial No. 579,935.

• *To all whom it may concern:*

Be it known that I, ALEXANDER E. LITTLE, a citizen of the United States, residing at Lynn, county of Essex, State of Massachusetts, have invented a certain new and useful Improvement in Boots and Shoes, of which the following is a specification, reference being had therein to the accompanying drawings.

10 My invention has for its object a new and improved boot or shoe which shall give to the longitudinal arch of the foot more efficient support, and hence be more healthful than shoes as heretofore constructed, but 15 which shall be flexible in the shank, and therefore easy and comfortable to the wearer, and which can be manufactured at substantially the same cost as other shoes of like quality as usually constructed. A more 20 particular object of my invention is to provide a shoe which shall operate so that the pressure of the foot on the inside of the shoe when the wearer is standing squarely will hold the shank of the shoe closely 25 against the underside of the instep instead of causing or permitting it to sag away from the instep.

I have found from careful study and long experience that welt shoes as ordinarily 30 constructed have an injurious effect on the foot, since the shank tends to drop away from the instep of the wearer, thus failing to support the longitudinal arch of the foot. Attempts have been made to provide less 35 injurious shoes by so constructing them that the upper acts as a bandage around the instep when the lacings or other securing devices are tightly secured, but in such shoes the tendency of the shank to flatten is increased and the injury to the foot is intensified rather than diminished. Moreover, in such shoes the bandage effect is 40 practically limited to that part of the foot forward of the top of the instep immediately over the cuneiform bones, since the lacings or other fastenings do not exert any material upward strain upon the upper to the rear of this point, so that, while the cuneiform and metatarsal bones are 45 firmly held, the scaphoid and astragalus are not materially supported, although these are the bones most needing support, since they are located at the top and, in effect, 50 constitute the "keystone" of the longitudi-

dinal arch. In accordance with my invention the last named bones of the longitudinal arch, as well as those forward thereof, are given adequate support.

I attain these results in part by using an insole having an extension which I term a saddle lying within the upper and extending beyond the inside edge of the outsole, the counter being extended forwardly so that it overlaps the rear end of the saddle, thus forming a continuous support for the inside of the foot. The upper and other parts are cut and proportioned so that the wearer's weight which flattens the sole will stretch the upper along a line drawn from the heel seam to the ball and thus tend to lift the upper particularly on the inside above the shank with the result that the whole semiflexible shank, composed of the outsole, upper, lining and counter stitched together through and through under heavy pressure, is lifted upward.

In welt shoes as heretofore constructed, the weakest point is at the inner side of the shoe about where the heel joins the shank. Accordingly, another object of my invention is to strengthen this portion of the shoe without, however, impairing the flexibility of the shank. This is accomplished by stopping the welt short of the ball of the foot at the inner side of the shoe, wrapping the upper flat across the insole at the inner side of the shank, and securing the insole, outsole and upper firmly together at this point by a through-and-through lock stitch seam which passes all the way through the several superposed layers of material, this seam preferably having its thread locks embedded in the outsole and welding the parts firmly together without affecting the flexibility of the whole.

The construction last described may to advantage be employed in connection with the arch supporting structure first mentioned, in which case the lock stitch seam passes through the extended and overlapping end of the counter as well as through the insole, outsole and upper, thereby uniting these parts with the firmness, while affording them the flexibility, required in order to enable them to function in the desired manner.

I am aware that shoes have been made with so-called "stabbed" shanks; that is,

with a line of stitching placed by hand along the inside edge of the shank, passing through the outsole, the upper and a lip on the insole but not completely through the insole. I am also aware that shoes have been "stabbed" along the shank by the use of McKay sewing machines, but, besides the defects inherent in McKay shoes, such shoes are stiff in the shank and are lacking in the good qualities resulting from the peculiar construction of the related parts described herein and particularly the insole with its saddle and the overlapping counter. The seam forming part of the herein-described invention does not oppose the bending of the shoe, since the locks of the stitches lie within the outsole and pivot or swing on each other when the sole is bent in much the same manner as the links of a simple cable chain swing on each other when the chain is bent.

The invention will be fully understood from the following description of one embodiment thereof, and its novel features will be pointed out and clearly defined in the claims at the close of this specification.

In the drawings, Fig. 1 is a plan view of a shoe embodying the invention, part of the upper being drawn aside to show the interior construction.

Fig. 2 is a vertical section of the shoe shown in Fig. 1.

Fig. 3 is a section on the line 3-3 of Fig. 2.

Fig. 4 is a section on the line 4-4 of Fig. 2.

Fig. 5 is a plan view of an insole employed in the shoe shown in Figs. 1 and 2.

Fig. 6 is a bottom plan view of the shoe showing the relation of the parts before the shoe is bottomed.

Fig. 7 is a diagrammatic side elevation, illustrating how the wearer's weight, when standing squarely on the ground, tends to lift the shank, holding it up against the wearer's instep.

Referring now to the drawings, at 11 is shown the outsole, at 12 the welt, at 13 the upper, at 14 the counter, and at 15 the insole. The outsole 11 is of ordinary construction except that the inside edge of the shank, as indicated at *a* in Figs. 1 and 3, is carried well in under the instep, curving outwardly about to, or even beyond, the median line of the shoe. This makes a narrow shank which is consequently very flexible and brings the point of connection of the sole and upper very far under the instep, thus permitting the upper, when secured tightly in place by the usual lacings or other fastening devices, to grip the foot in substantially the manner of a bandage tending to support the forward portion of the inner side of the instep. The insole 15 is provided, adjacent the shank or instep portion, with

a lateral extension 16 which for convenience I call a saddle. The insole with its extension or saddle is preferably made of material which will be elastic and yielding, although sufficiently stiff to perform the functions hereinafter referred to. The saddle lies inside the upper and extends inwardly and upwardly from the inside edge of the shank of the shoe, re-inforcing the upper and distributing rearwardly the supporting strain of the bandage portion of the upper, thereby affording support to the rear portion of the longitudinal arch of the foot.

The counter 14 is long enough to overlap part of the saddle 16 and to be stitched through and through and become part of the shank. In the finished shoe, the saddle and counter merge into each other along the inside of the shoe and together support this portion of the foot and hold up the shank of the shoe in accordance with the distribution of weight, as will be explained more in detail later.

In constructing the shoe embodying my invention, the upper along the inside of the shank is wrapped across and caused to lie substantially flat upon the bottom of the shank portion of the insole, as shown at *b* in Figure 6, being cut accordingly, and is suitably secured thereto as by a line of stitches 17. The welt 12 is started at the point *c* substantially at the breast of the heel at the outer side of the shoe and carried around the toe and stops at the point *d* at the inner side of the shoe opposite the ball of the foot, this being at the front end of the saddle 16. There is, therefore, no welt adjacent the saddle. The outsole 11 is secured to the shoe in the ordinary way except along the inside of the shank where there is no welt. In the drawings, I have shown at 18 the stitching by which the outsole is secured to the welt. Thereafter, I stitch the shoe along the inside of the shank, as shown at 19 in Figures 1, 2, 3, and 4. This line of stitching follows closely the edge of the outsole and passes all the way through the several superposed layers of material including the outsole, (with the exception of the usual channel, if such be used), the insole, the elongated counter and the upper. The seam is a lock-stitch seam and the locks are set inside the outsole. This is a very important feature of my invention because it gives great strength to the shoe without diminishing its flexibility. This line of stitching, which is inserted under heavy pressure, secures the insole, outsole, upper and counter together, and since it is preferably a lock stitch seam, the several stitches hinge on each other like the links of a chain and do not reduce the flexibility of the shank although firmly welding the parts together. No metal or other stiffening material is used in the shank. The overlap-

ping of the counter and saddle together with the strength given to the shoe by this line of stitching 19 renders the shoe strongest at the point where the counter overlaps the saddle of the insole which is the weakest point in shoes of ordinary construction.

The upper and other parts of the shoe are proportioned and cut so that when the shoe is flat, as is the case when the wearer's weight is evenly distributed over it, the upper along a line from the heel seam at the point *e* (see Fig. 7) to the ball at about the point *g* is stretched or drawn taut. Since the upper is carried down and under the saddle to the edges of the outsole and is secured to it by the line of stitching described, the stretching of the upper along the line *e*, *g* draws it tight around the inside of the instep and holds the flexible shank up against the foot. The inside forward end of the counter which extends to about the middle of the saddle tends to lift the shank whenever there is any pressure on the inside of the counter at the heel, thus assisting the upper and saddle to hold the shank up against the foot. This completely prevents the sagging or dropping of the shank which is always to be observed in welt shoes as heretofore constructed. The saddle and forwardly extending counter are thus held firmly but yieldingly against this portion of the foot and together form a sort of yielding cradle in which the foot rests comfortably. When the weight is taken from the heel and thrown forward onto the ball as in the act of walking, the pressure is released and the whole shoe flexes with the foot. The pressure placed on the inside of the instep of the wearer's foot by this construction, in which the upper is stretched tightly across this portion of the foot together with the saddle, tends to throw the foot into natural position throwing the weight toward the inside of the shoe. It has previously been attempted to accomplish this result by the use of wedges and raising and lengthening the inside corners of the heel.

I find from careful observation of the action of the shoes embodying my invention 50 that the longitudinal arches of the wearer's foot, even when already seriously weakened, tend to grow stronger because of the perfectly distributed support afforded at the instep, and that in this respect my shoes are 55 a great contrast to ordinary welt shoes.

This case is in the nature of a continuation, in part, and with respect to the subject matter common to the two cases, of my prior application filed June 15, 1922, Serial Num- 60 ber 568,539.

What I claim is:—

1. A boot or shoe including an upper, an outsole and an insole, the insole having on the side thereof a saddle between the ball 65 and heel which extends beyond the outsole, a welt which stops short adjacent the front end of the saddle, and a counter overlapping the saddle for a portion of its length, said parts being secured together along the 70 inside of the shank by a lock stitch seam extending all the way through said insole, outsole, upper, and counter.

2. A boot or shoe including an insole, an upper which along the inside of the shank 75 is wrapped across and lies flat against the underside of the insole, the edge of said upper being stitched in place, a welt stopping short of the ball of the foot on the inside, an outsole and a lock stitch seam 80 along the inside of the shank extending all the way through the insole, outsole, and upper.

3. A boot or shoe including an insole, an upper which along the inside of the shank 85 is wrapped across and lies flat against the under side of the insole, the edge of said upper being secured to said insole, a welt stopping short of the ball of the foot on the inside, an outsole, and a lock stitch seam 90 along the inside of the shank extending all the way through the insole, outsole and upper.

In testimony whereof I affix my signature.

ALEXANDER E. LITTLE.
